UNITED STATES PATENT OFFICE.

ROBERT F. PHILLIPS, OF CARRICK, PENNSYLVANIA.

DESIGN FOR A CAR-WHEEL.

No. 38,228.

Specification for Design.

Patented Sept. 4, 1906.

Application filed July 12, 1906. Serial No. 325,976. Term of patent 14 years.

To all whom it may concern:

Be it known that I, ROBERT F. PHILLIPS, a citizen of the United States, residing at Carrick, in the county of Allegheny and State of Pennsylvania, have invented a new, original, and ornamental Design for Car-Wheels, of which the following is a specification.

My design for a car-wheel is shown in the accompanying drawing, in which is illustrated a face view of the wheel.

I claim—

The ornamental design for a car-wheel as shown.

ROBERT F. PHILLIPS.
